Des. 67,469

UNITED STATES PATENT OFFICE.

JOSEPH NATHANSON, OF SAN FRANCISCO, CALIFORNIA.

DESIGN FOR A VANITY CASE.

Application filed May 31, 1922. Serial No. 2,480. Term of patent 3½ years.

To all whom it may concern:

Be it known that I, JOSEPH NATHANSON, a citizen of the United States, residing in the city of San Francisco, State of California, have invented a new, original, and ornamental Design for a Vanity Case, of which the following is a specification, reference being had to the accompanying drawing, forming part hereof.

I claim;

The ornamental design for a vanity case, as shown.

JOSEPH NATHANSON.
